UNITED STATES PATENT OFFICE.

CONRAD M. PITEL, OF MERIDEN, CONNECTICUT.

EXTENSION-CHANDELIER.

1,113,480.

Specification of Letters Patent. Patented Oct. 13, 1914.

Application filed February 26, 1913. Serial No. 750,759.

To all whom it may concern:

Be it known that I, CONRAD M. PITEL, a citizen of the United States, residing at Meriden, in the county of New Haven and 5 State of Connecticut, have invented a new and useful Improvement in Extension-Chandeliers; and I do hereby declare the following, when taken in connection with the accompanying drawings and the characters of reference marked thereon, to be a full, clear, and exact description of the same, and which said drawings constitute part of this 10 application, and represent, in—

Figure 1 a side view of an extension fixture constructed in accordance with my invention. Fig. 2 a sectional view of the same. Fig. 3 a transverse sectional view on the line *a—b* of Fig. 2.

This invention relates to an improvement 20 in chandeliers for electric lights, gas or combination gas and electric lights, and in which some of the lights are fixed, while others are movable vertically, and particularly for chandeliers of the shower type.

25 The object of this invention is to provide a flexible conduit for the movable light, and to provide a shell or casing in which the flexible conduit may be coiled; and the invention consists in the construction herein- 30 after described and particularly recited in the claims.

In carrying out my invention as shown in Figs. 1 and 2 of the drawings, I employ a comparatively large shell or casing 2 which 35 incloses the usual spring suspension device 3 which is connected at the top with a coupling-piece 4 for the attachment to the usual gas nipple, and at the bottom with a bar 5 into which extends the upper end of an 40 outer pipe 7 through which the flexible conductor tube 8 extends. This flexible conductor tube leads from the upper part of the coupling-piece 4 through the outer pipe 7 into connection with the upper end of a 45 burner pipe 9 leading to the usual burner 10 and electric wires or gas pass through this conductor. The cable 6 from the suspension device is also connected with this pipe 9. Carried by the pipe 7 is a crown or 50 arms 11 which support pendant fixtures 12 for electric lights fed by wires 13 and passing downward through the shell 2 and following suspension chains 15 in the usual manner of wiring electric lights of the so 55 called "shower" type. Instead of providing for adjustment of the spring suspension

device 3 in combination fixtures, as is common in extension chandeliers, I may, as shown in Figs. 1 and 2 of the drawings, surround the pipe 7 at intervals with collars 16 60 forming supports for set screws 17 which extend through the pipe 7 and bear against a longitudinally split pipe 18 between the tube 7 and the pipe 9 between which pipes, if desired, suitable packing 19 may be placed. 65 By turning the screw 17 in or out the friction may be so adjusted that the drop light 10 will remain in whichever position it is moved, the spring of the tension device 3 being sufficient to prevent its dropping. The 70 friction produced by the split pipe is sufficient to support a light weight lamp without the aid of a suspension device. When the burner 10 is drawn down the flexible conductor tube 8 which has been coiled 75 within the shell 2, will uncoil and permit of the downward movement of the burner 10. Then when the burner 10 is moved upward the flexible conductor tube will coil itself within the shell 2 by which it is entirely hid- 80 den from view.

I claim:—

1. An extension chandelier comprising a coupling-piece, a frame secured to the coupling-piece, a spring drum within said 85 frame, a shell surrounding the frame, a pipe extending downward through the shell, a hollow rod extending through said pipe, cable connections between the rod and the drum, a drop light secured to the said rod, 90 and a flexible electric conductor tube between the rod, and the source of supply, said flexible conductor tube also extending through said pipe and adapted to be coiled horizontally within the shell beneath the said drum. 95

2. An extension chandelier comprising a coupling-piece, a frame secured to the coupling-piece, a shell surrounding the frame, a pipe extending downward through the shell, a hollow rod extending through said 100 pipe, a drop light secured to said rod, and a flexible conductor tube between the rod and source of supply, said flexible conductor tube also extending through said pipe and adapted to be coiled horizontally in the said 105 shell.

3. An extension chandelier comprising a suspension device, a shell inclosing the same, an outer pipe supported by said suspension device, a drop light, a burner pipe connected therewith and extending into said outer pipe, 110 cable connections between the burner pipe

and the suspension device, a flexible conductor tube extending from said drop light through said outer pipe, a split pipe surrounding the burner pipe, and screws extending through the outer pipe into engagement with said split pipe whereby the diameter of the split pipe may be adjusted.

4. An extension chandelier comprising a coupling-piece, a frame secured to the coupling-piece; a shell, a tube extending downward through the shell; a burner pipe extending through said tube, a drop light secured to said burner pipe, a flexible conductor extending through said tube to said

burner pipe, a split tube surrounding the burner pipe, a frictional packing between the tube and pipe, and screws extending through the tube into engagement with said split tube whereby the diameter of the split tube may be adjusted.

20 In testimony whereof, I have signed this specification in the presence of two subscribing witnesses.

CONRAD M. PITEL.
